United States Patent Office

Des. 180,219
Patented May 7, 1957

180,219

SPECTACLE FRAME FRONT

Marcel Arnaut, Paris, France, assignor to Societe Industrielle de Lunetterie, Paris, France

Application August 2, 1956, Serial No. 42,486

Term of patent 7 years

(Cl. D57—1)

Fig. 1

Fig. 1 is a front elevational view of a spectacle frame front showing my new design; and

Fig. 2 is a top plan view thereof.

I claim:

The ornamental design for a spectacle frame front, as shown.
